Application July 17, 1943, Serial No. 495,113

14 Claims. (Cl. 214—18)

2

1 This invention relates to metallurgical furnaces of the controlled atmosphere type and more particularly to conveying and quenching mechanism for the parts to be heated therein.

This application contains certain subject matter originally described in my applications Serial Nos. 384,641 and 455,720, filed March 22, 1941, and August 20, 1942, respectively, now Patents Nos. 2,346,698 and 2,394,002.

Briefly, the aforesaid applications relate to the production of a lithiated furnace atmosphere in which the atmosphere may be composed of gases resulting from the reaction of a hydrocarbon fuel and air at a relatively high temperature to which is added the vapor of a compound or compounds of lithium. Such an atmosphere, when properly produced, is substantially free from moisture and is non-oxidizing to metals heated therein. It may be either carburizing or non-carburizing, depending upon the proportion of carbon monoxide and methane therein. The parts treated in such a lithium atmosphere become coated with a thin protective layer of lithium compounds so that, if desired, they may be removed from the furnace and cooled in air without oxidation, or they may be quenched directly from the furnace atmosphere.

The present invention is concerned with conveying and quenching mechanism for such a furnace in which the conveyor may be moved to or through the door opening of the furnace for loading, then into the furnace for heating of the parts and, after the treatment is completed, moved either to or through the door for removal of the parts or moved into position to discharge the parts directly from the atmosphere into a quenching medium without necessitating the opening of the furnace door.

One of the objects of the present invention is to permit all or a part of the work parts to be discharged directly from the furnace atmosphere into a quenching medium without passing through or in contact with the air.

Another object is to provide a conveyor mechanism which may be moved into position to discharge the work parts into the quenching medium without opening of the heating chamber to the air.

Another object is to provide means for directing the conveyor into position to discharge the work parts either into the quenching medium or in position to permit loading or unloading thereof through the furnace door.

Another object is to control the path of movement of the conveyor in accordance with the open or closed position of the door.

Another object is to provide a novel conveyor mechanism for a heat treating furnace which is simple, sturdy and convenient to operate.

Another object is to provide a novel quench chute and supporting means therefor.

Other objects and advantages will hereinafter appear.

The quenching mechanism comprises a chute extending directly from the heating chamber of the furnace into a tank containing the quenching medium. The conveyor comprises a flexible or jointed bed of a length corresponding approximately to that of the heating chamber and the throat of the quench chute is provided with movable bridging means whereby to direct the conveyor either across the throat for movement to or through the furnace door or to permit it to move into the quench chute for discharge of its load therein. The bridging member may be controlled in relation to the open or closed position of the door so that forward movement of the conveyor, with the door closed, will cause discharge of the work parts into the quench chute whereas forward movement of the conveyor when the door is open will cause the conveyor to move to or through the door opening.

The invention will be more fully understood by reference to the accompanying drawings wherein:

Fig. 1 is a vertical sectional view of an atmosphere furnace embodying the present invention;

Fig. 2 is a fragmentary perspective view of the muffle of such a furnace illustrating the conveyor mechanism and quench chute;

Fig. 3 is a sectional view on the line 3—3 of Fig. 2;

Fig. 4 is a view similar to Fig. 2 showing a modified form of conveyor and quench chute;

Fig. 5 is a fragmentary view of the conveyor guiding means for the quench chute shown in Fig. 4;

Fig. 6 is a fragmentary view of one form of a flexible conveyor;

Fig. 7 is a fragmentary view of a different form of flexible conveyor; and

Fig. 8 is a vertical sectional view of a modified furnace provided with a quenching chute and a cooling chamber.

Referring first to Fig. 1, in which the mechanism of the present invention is shown applied to a furnace of the lithiated atmosphere type, the numeral 10 indicates a muffle of rectangular section composed preferably of a heat resisting metal, such as nickel or nickel-chromium alloy. The muffle extends, at the forward end, through a rectangular opening 11 in a refractory com-

bustion chamber 12, and the rear of the muffle terminates within an opening 13 in the rear wall of the chamber 12. The forward end of the muffle is provided with a flange 14 to which is secured a muffle extension 15 provided with a suitable door 16 at its outer end. The door may be controlled by a foot pedal 17 connected thereto through a flexible cable 18 passing over suitable pulleys 19 and 21. The pedal 17 is pivoted at 22 and is adapted to be held in suitable raised position by means of a latch 23 thereon engaging in suitable notches in the serrated plate 24. Extending downwardly from the muffle extension 15 is a quenching chute 25 which terminates beneath the body of quenching medium 26 contained within a suitable receptacle 27.

The muffle 10 is heated by two series of burners 28 extending into the combustion chamber 12 at opposite sides thereof beneath the muffle 10. The burners 28 are supplied with a combustible mixture of air and gas from a manifold 29. The combustion chamber 12 is vented by a plurality of pipes 30 extending from a point above the center of the muffle 10, through the refractory insulation, and terminating above the furnace shell.

Situated to the rear of the combustion chamber 12 is a vaporizing unit 31 and a gas generating unit 32. The vaporizing unit 31 includes a combustion chamber 33 provided with burners 34 supplied with a combustible mixture of gas and air from a manifold 35, and is vented by ports 36. The air and gas lines 37 and 38 are each provided with two branches, the branch air lines having electrically controlled valves 39 and 41 therein, by which air under suitable pressure is supplied to a pair of Venturi mixing tubes 42 and 43, respectively, connected to the manifolds 39 and 35 associated with the burners 28 and 34, respectively. The two branches of the gas line 38 are provided with pressure regulating valves 44 and 45, the outlet sides of which are connected to the throats of the Venturi tubes 42 and 43, respectively. The valves 39 and 41 are operated under the control of thermocouples located in the combustion chambers 12 and 33, respectively.

The gas generating unit 32 comprises a substantially rectangular combustion chamber 46 provided with suitable burners 47, vents 48 and a cracking chamber 49. The cracking chamber is a substantially U-shaped chamber of a heat resisting metal or alloy and is provided with inlet and outlet conduits 50 and 51 connected into the free ends of the opposite arms of the cracking chamber. The inlet conduit 50 is connected to a suitable source of gas and air, such as described in my aforesaid application Serial No. 455,720, and comprising, briefly, a plurality of gas control valves 52a-c and associated air control valves 53a-c, whereby different ratios of gas and air may be readily obtained. The gaseous mixture is forced, by a pump 54, under a slight pressure into the cracking chamber 49. The gas and air mixture is heated in the chamber 49 to the cracking temperature, from about 1400° F. to 1900° F., to effect a reaction between the gases after which they are conducted by the outlet conduit 51 into a condenser 55 wherein they are cooled to approximately room temperature, to remove a portion of the water vapor therefrom. The partially dried reaction products are then conducted by a conduit 56 into a lithium compound vaporizing chamber 57 suspended in the combustion chamber 33. The chamber 57 has

an open top, closed by a close fitting cover 58, through which a cartridge 59, containing lithium compounds, may be introduced into the chamber. A partition plate 61 depending from the cover 58 causes the incoming gases to be deflected over the cartridge 59 so as to entrain the vapors therefrom and to carry the same through the conduit 62, into the muffle 10.

The lithiated reaction products may be either neutral or carburizing depending upon the ratio of gas and air admitted into the cracking chamber. In either case, the presence of lithium renders the gas substantially dry and non-oxidizing to the work parts introduced into the muffle. The work parts after treatment may be removed from the muffle and air cooled, or they may be quenched directly from the protective atmosphere. The present invention is concerned with the conveying and quenching mechanism by which the parts may be carried into and out of the furnace for either air cooling or for quenching. This mechanism will now be described by reference to Figs. 1 and 2.

Located on the floor of the muffle 10 and adapted to slide thereon is a conveyor 63 composed of a series of flat plates 64 having a portion at each side bent upwardly to form a flange 65. The successive units are coupled together by links 66 loosely pivoted to the outer sides of the adjacent ends of the flanges 65. The individual plates may be of any convenient length, except they must not be longer than the depth of the throat of the quench chute 25, since it is necessary that they pass into the quench chute under conditions as will hereinafter appear. The rear plate 64' has a drawbar 67 pivotally secured thereto and extending forwardly through the muffle and through a suitable slot 68 in the door 16, thus permitting the conveyor to be moved forwardly or backwardly in the muffle. The connection of the drawbar 67 to the rear of the conveyor leaves the forward end thereof free to pass into the quench chute as the conveyor is drawn forward, as will hereinafter appear.

The quenching chute 25 adjacent its upper end is provided at the rear thereof with an angular extension 69, bridged by a solid concave plate 71 and having three convex rails 72 extending thereacross. Pivoted at the juncture of the upper end of the chute 25 and the forward end of the muffle extension 15 is a bridging member 73 which normally extends downwardly against the forward wall of the chute 25, as shown in dotted lines. This member is secured to a shaft 74 extending externally of the chute where it is provided with an operating arm 75 pivoted to the upper end of a plunge rod 76 having a piston 77 working within a cylinder 78 mounted on a pivot 79. The plunger is adapted to be operated pneumatically to move the bridging member 73 from the position shown in dotted lines in Fig. 1 to the horizontal position shown in full lines so as to bridge the upper end of the chute 25. The bridging member comprises two arms which extend between the rails 72. It is controlled by means of suitable electric valves 81 and 82 operated by means of the foot pedal 17 through the mercury switches 83 and 84. The cylinder 78, at its upper end above the piston 77, is connected by a flexible conduit 85 to a source of low pressure air, and at its lower end, beneath the piston, it is connected by a flexible conduit 86 to the valve 82 by which it may be supplied with high pressure air. The valve 81 provides a vent from the conduit 86 to the outer air. With the door 16 closed, the

mercury switch 84 is open and the winding of the valve 82 is deenergized while the mercury switch 83 is closed and the winding of valve 81 is energized to maintain the former closed and the latter open, connecting the conduit 86 to the atmosphere and permitting the low pressure air to maintain the plunger depressed and the bridge member 73 in its downward position clear of the throat of the chute 25. However, when the foot treadle is depressed, to open the door 16, the switch 83 opens, deenergizing the valve 81 to close the same, and the switch 84 is closed to energize and open the valve 82, thus permitting the high pressure air to enter beneath the piston 77 to raise the same against the opposing force of the low pressure air, thereby to move the bridge member 73 to its upward or horizontal position so as to bridge the throat of the chute 25. In this position of the member 73, the conveyor elements 64 may be withdrawn to the forward end of the furnace adjacent the door for loading. After they have been loaded and positioned within the muffle 10, the door 16 may be closed by the upward movement of the pedal 17. The switches 84 and 83 reverse the positions of the valves 81 and 82 so as to exhaust the lower portion of the cylinder 78 and permit the low pressure air supplied to the upper portion thereof through the conduit 85 to return the bridging member 73 to its vertical position adjacent the front wall of the chute 25. When the carburizing or heat treating operation has been completed, the drawbar 67 is drawn forward, with the door 16 closed, thus pulling the conveyor elements to the throat of the chute 25 down which they then travel by gravity, permitting the treated parts thereon to be dumped one after the other through the chute 25 and into the quenching bath 26. The conveyor may be advanced to the throat of the quench chute at such rate, depending on the nature of the load and the rate of circulation of the quenching medium in the quench tank, as to keep the parts sufficiently separated to enable the oil to absorb the heat therefrom without local overheating at the base of the chute, whereby an even quench and uniform hardness is obtained. The atmosphere for the muffle 10 is exhausted through the vent 87 which extends from a point adjacent the lower end of the quenching chute 25 upwardly to above the level of the muffle and as it escapes into the open air, it is ignited by means of a pilot burner 88 having a conduit 89 connected to the gas line 38.

At times in the treatment of certain steels it may be necessary to cool the treated parts to near or below the lower limit of the critical temperature before quenching, and for this purpose it is convenient to draw the conveyor with its work parts into the muffle extension for such precooling in the lithiated atmosphere. In such cases it is necessary to maintain the bridging member 73 in its bridging position while the door 16 remains closed. For this purpose I have provided a manual switch 90 of the double pole type, in circuit with the windings of the control valves 81 and 82. Normally this switch is in the upper position shown in Fig. 1, but when it is desired to raise the bridging member 73 independently of the closed position of the door, the switch is moved to its lower position, thereby interrupting the circuit to the vent valve 81 to close the same and applying current to the high pressure air valve 82 to open the same, thereby to raise the bridging member. The conveyor may then be moved to the forward end of the muffle for pre-

cooling, after which it may be again moved backward into the muffle, the switch 90 raised to effect a lowering of the bridging member and the conveyor again drawn forward to deposit its charge into the quench chute.

It will be noted, therefore, that after the parts have been loaded in the furnace and the door closed, they are continuously subjected to the atmosphere introduced through the conduit 62 into the muffle 10 until they enter the quenching bath.

The circulation of the lithiated gases in the chute 25 also causes a portion of the lithium or its compounds to be taken up by the oil which is continuously circulating in the base of the quench chute and to be mixed therewith. Due to the sudden condensation of the vapor of lithium or of the carbonate or oxide thereof, upon contact with or entrainment by the cool oil, this material solidifies in an extremely fine state of subdivision and in this state these alkali salts are particularly effective saponifying agents for lard oils or other fatty oils which I provide in the oil, thus producing soaps or metallic esters of the fatty acid which greatly increase the wetting properties of the oil. These metallic esters are formed primarily in the base of the quench chute where the work first comes in contact with the oil. As a combined result of the oil circulation in the quench chute and the increased wetting property of the oil, there is a complete absence of frothing in or adjacent the base of the quench chute and better and more even quenching of the work parts results.

In addition to this increased interfacial tension of the quenching oil with the work parts, the absorption of lithium carbonate into the oil neutralizes the free acid in the oil and thereby prolongs the useful life thereof. In the absence of this absorbed lithium and lithium compounds, the fatty acid content of the oil oxidizes and becomes rancid. As the acid content thus builds up the physical characteristics of the oil are modified and its quenching properties altered. In addition the fatty acids solidify and accumulate in the oil and upon contact with the work parts prevent proper contact of local areas thereof with the quenching medium.

The quench chute 25, as stated, is secured to the forward end of the muffle and is supported in part thereby. To provide additional support while permitting the forward expansion of the muffle, a bracket 91 (Figs. 1, 2 and 3) is mounted on the forward wall of the furnace. Carried by the bracket 91 is a transverse plate 92 having two bolts 93 threaded therein and locked in place by nuts 94. The heads 95 of the bolts 93 are machined flat and adjusted into engagement with the underside of the angular extension 69 of the chute 25. The muffle 10 is anchored at its after end by a pin 96 and, as it is brought up to heat, it expands forwardly, causing the quench chute to slide outwardly on the heads of the bolts 93. The overhanging ends of the plate 92 provide sufficient rigidity to give the required support to the chute 25, but are also sufficiently resilient to prevent binding of the muffle in the front wall of the furnace.

The conveyor arrangement shown in Figs. 1 and 2 is suitable for small furnaces in which the length of the conveyor is less than the height of the quench chute above the level of the quenching medium 26. It is not desirable, however, to have the conveyor elements enter the quenching medium since the frequent heating and quench-

ing thereof tends to deteriorate and dirty the same.

In Fig. 4 I have shown a modified form of conveyor and quench chute adapted for longer muffles. In this modification the work conveying belt 101 is in the form of a woven or mesh belt having a series of upstanding pivoted links 102 along the sides thereof to form a trough. The links 102 have offset, overlapping pivoted ends, as more clearly shown in Fig. 6. Lateral tabs 103 bent out from the body of the links form anchorages for the strands of the mesh portion 104 of the conveyor. The conveyor is free at its forward end and is secured to a drawbar 105 at its rear end, similar to the drawbar 67 of Figs. 1 and 2, whereby the conveyor may be moved to and fro along the floor of the muffle.

The quench chute 106 is provided with the same throat or bridging member 73 described in connection with Figs. 1 and 2, across which the conveyor may be drawn to or through the door opening of the muffle to enable the conveyor to be loaded with the parts to be treated. After loading of the conveyor it is moved to the rear of the muffle by the drawbar 105 and the door 16 closed. The closing of the door lowers the bridging member against the front face of the chute 106 as shown.

After the treatment of the parts has been completed they may either be removed from the furnace and cooled in the air or quenched, as desired. If they are to be air cooled, the door is again opened, which, as described, causes the bridging member 73 to be raised whereby the conveyor may be drawn forwardly to or through the door opening. If they are to be quenched, however, the door remains closed so that the bridging member remains lowered as the bar 105 is drawn forward. During this movement, the forward end of the conveyor drops by its own weight into the chute 106, engaging between the curved rails 107 and a pair of spaced guide fingers 108 whereby the conveyor is directed into a receptacle 109 formed to the rear of the quench chute. The curvature of the rails 107 and the guides 108 is such that the conveyor overhangs the rear wall of the chute 106 so that the work parts as they fall from the conveyor pass freely through the chute into the quenching medium. During the forward movement of the conveyor it accumulates in the chamber 109 and is thus protected from engagement with the quenching medium and thus the deteriorating effect of frequent quenching is avoided. The belt also remains clean and the quenching medium is not carried into the muffle on the conveyor, as would be the case if the conveyor was permitted to enter the quench tank.

In the case of short conveyors, for use in small furnaces, the front section of the conveyor may be brought to the door of the muffle and the conveyor loaded or unloaded, as by means of tongs or other work handling means, through the open door of the muffle. However, in the case of long conveyors, this method of loading and unloading of the conveyor is cumbersome and, therefor, I provide a conveyor support adjacent the door upon which the conveyor may be positioned for loading and unloading. This supporting means may comprise a pair of rails 111, secured to a shaft 112, pivoted beneath the muffle extension on any suitable bracket 113, in such a way that the rail assembly normally rests against the front wall 114 of the quench chute cover, as indicated in dotted lines in Fig. 4, but

are movable to the full line position to form a continuation of the muffle floor, upon which the conveyor may be drawn for loading or unloading. A folding strut 115 is pivoted at its lower end on a trunnion 116 carried by the wall 114 and at its upper end to the inner side of the rail members 11. This strut comprises an upper pair of arms 117 hinged at 118 to the outer sides of a lower arm 119 in such manner that when the rails are lowered against the wall 114, the strut folds against this wall with the arms 119 and 117, and the rails 111, in nested relation. Lateral extensions 120 on the lower arm 119 prevent movement of the hinge beyond the aligned position of the arms, as shown, and thus impart rigidity to the strut.

In Fig. 7 I have shown a modified form of conveyor in which the upstanding edge 121 is woven as an integral part of the body portion 122 of the conveyor. The drawbar 123 is secured to a plate 124 welded to the flange portion 121 at its rear edge. It has been found that such a structure is sufficiently flexible to readily enter the quench chute 106 and the storage chamber 109. The flanged edges 121, however, impart sufficient rigidity to the conveyor so that it may be moved to and fro along the muffle floor smoothly and without buckling.

It will be understood, of course, that in place of the woven mesh structure, a link or other form of flexible belt may be employed. The conveyor is preferably composed of a heat resisting metal such as nickel or nickel-chromium alloy, but this is not essential since the good life is obtainable with conveyors composed of steel since they are continuously under the protection of the lithium atmosphere while in the muffle 10 and the storage chamber 109, and are protected by the coating of lithium compounds when withdrawn to or through the door opening for loading and unloading. In order to prevent stagnation of the lithiated atmosphere in the chamber 109, it is connected to the quench chute vent pipe 87 by a conduit 125 (Fig. 4) so as to permit gas circulation therethrough.

In Fig. 4 I have shown a modified form of support for the muffle extension and quench chute 106, comprising a pair of brackets 126 each composed of a horizontally disposed angle 127, a vertical angle 128 and an intermediate gusset plate 129. The brackets are secured to the front wall 131 of the furnace, adjacent each side of the quench chute, as by bolting or welding, and the horizontal angles support a pair of roller brackets 132. The quench chute 106 has secured to each side thereof an angle 133 positioned so as to rest upon the rollers 134 whereby the muffle is supported in a manner to permit it to move fore and aft as the muffle expands and contracts.

While it is ordinarily preferable to employ a conveyor in connection with the quench chute, it is to be understood that this is not essential, and in Fig. 8 I have shown a quench chute and associated bridging member adapted for use when no conveyor is employed. In this arrangement it is contemplated that the parts will be pushed through the muffle in a continuous succession and either be quenched as they leave the rear of the muffle or pass over the bridging member into a cooling chamber, where they may be cooled in the lithiated atmosphere. In Fig. 8 the muffle is formed in two sections 136 and 137 secured to the intermediate quench chute 138. The front muffle 136 serves as the heating chamber and is

heated by a combustion chamber 139 having suitable burners 141 and vents 142. It is closed by a door 143 and is vented by a conduit 144 at its forward end. The rear muffle 137 serves as a cooling chamber and may be provided with a jacket 145 whereby a suitable cooling fluid may be circulated therearound. It has a vent 146 and is normally closed by a sliding plate or partition 147.

The lithiated atmosphere is shown entering at 10 the center of the muffle assembly and passing, by means of a T-coupling 148, into the conduits 149 and 151 extending respectively along the roof of the front and rear muffle sections 136 and 137. The conduits 149 and 151 are slotted, as at 152, 15 to permit entrance of the atmosphere into each of the muffle sections at spaced points therealong.

The quench chute 138 extends downwardly between the front and rear muffle sections into a quench tank 153 and is vented by a conduit 154 extending upwardly from the quench chute just above the level of the quenching medium. The throat or bridging member 155 is in the form of a solid plate secured to a pivoted shaft 156 operated by an air cylinder 157 in the same manner as shown in Fig. 1, except that it is controlled by means of a manual switch 158.

A heat baffle 159 in the form of a flexible chain or woven mesh curtain depends from the roof of the muffle and tends to isolate the cooling chamber from the heating chamber. A vestibule 161 in the form of an extension of the rear muffle 137 is provided with a door 162, which is normally closed when the slide 147 and the front door 143 are open, during the loading operation, so as to prevent an influx of air into the muffles. The door 143 and slide 147 are adapted to be operated either in unison or the front door 143 may be operated separately, depending upon whether the bridging member 155 is in bridging position or in its lowered position. The door 143 and the slide 147 are, respectively, operated by cables 163 and 164 passing over pulleys 165 and 166 and attached to the plungers of air cylinders 167 and 168. The air cylinders are supplied, above their respective plungers, with high pressure air by conduits 169 and 171 under control of a valve 172, and may be vented to the outer air by a valve 173. Low pressure air is continuously applied to the cylinders beneath the plungers by a conduit 174. The valves 172 and 173 are operated electrically under control of a push button type toggle switch 175, shown diagrammatically. With the lower button C depressed, switch contacts 176 are open, effecting closure of the valve 172 in the high pressure air line, and contacts 177 are closed to operate the valve 173 so as to vent the upper side of the plungers in the respective air cylinders to the outer air. The plungers are therefore raised by the low pressure air, permitting the doors to lower to their closed position. Depression of the upper button O operates the high pressure air valve 172 to open position and permits the vent valve 173 to close, whereupon the high pressure air above the plungers force the same downwardly, raising the door 143 and the slide 146.

The high pressure air line branch 171 for the rear cylinder 168 has a supplemental valve 178 therein which operates in parallel with the high pressure valve 179 of the bridge controlling cylinder 157 so that valve 178 is open only when the bridging member is in its raised position. With the manual switch 158 on its left contact to effect a lowering of the bridging member, the

valve 178 is retained closed and operation of the button O of switch 176 effects opening only of the entrance door 143.

The vestibule door 162 is operated by a cable 181 passing over pulley 182 and attached to the plunger 183 of an air cylinder 184. The high pressure air valve 185 and the vent valve 186 associated with the cylinder 184 are controlled by a manual switch 187. Contacts 188 of switch 187 are normally closed and are connected in circuit with the vent valve 186 so as to maintain this valve open so that the plunger in the cylinder is normally raised and the door 162 is closed. Contacts 189 of switch 187 are normally open and are connected in circuit with the high pressure valve 185 and contacts 171 of switch 175 so that valve 185 is normally closed. When it is desired to open the door 162, the switch 187 is operated to open the contacts 188 and to close contacts 189, thereby closing the vent valve 186 and opening the high pressure air valve 185. This latter valve is opened, however, only in case the switch 175 is in its closed position, that is, only when the front door 143 and the vestibule slide 147 are closed.

The lower wall or floor of the vestibule 161 slants downwardly and is provided with a series of anti-friction rollers 191 so that upon opening 30 of the door 162 any work parts which may be in the vestibule will be discharged therefrom. A suitable conveyor or work receiving table, not shown, may be disposed adjacent the door 162 to receive the parts discharged from the vestibule.

35 In the operation of this furnace the parts to be treated are introduced through the door 143 at intermittent periods, each work part serving to advance the entire line through the muffle assembly. If precooling is desired, the bridge member 155 is elevated by moving the switch 158 to its right hand position. The parts are then pushed across the member 155 and through the cooling chamber 137. When the entrance door 143 is opened to insert a cold part, the slide 147 is simultaneously opened to permit a cooled part to be removed from the cooling chamber into the vestibule 161. However, if the parts are to be quenched, the switch 158 is placed on its left contact, lowering the bridge member 155 and closing the valve 178 so as to retain the slide 147 closed. Each new work part introduced into the heating chamber will thus push a heated part into the quench chute, through which it falls into the quenching medium in the tank 153.

40 It will be understood, of course, that other arrangements and constructions of the quench chute, its bridging member and the conveyor mechanism may be devised and I, therefore, do not desire to be limited to the exact constructions and arrangements shown, but contemplate all forms thereof coming within the scope of the appended claims.

45 What I claim is:

1. In a furnace, the combination of a chamber having a heating section and a loading section, a door normally closing said chamber adjacent to said loading section, means for operating said door to an open position, a flexible conveyor having oppositely disposed ends, said conveyor providing a continuous work holding surface movable to and fro in said chamber between said loading and heating sections, and means extending through said door and secured to one end 50 only of said conveyor for actuating said conveyor for actuating said conveyor.

veyor in either direction in said chamber in either the closed or open position of said door.

2. In a furnace, the combination of a chamber having a heating section and a discharge section, a door normally closing said chamber, an articulated conveyor having oppositely disposed ends and providing a continuous work holding surface movable to and fro in said chamber between said heating section and said discharge section, a single means for actuating said conveyor in either direction in said chamber, a discharge opening in the base of the discharge section of said chamber, and means for directing one end of said conveyor into said discharge opening.

3. In a furnace, the combination of a heat treating chamber having a heating section and a discharge section, a door normally closing said chamber, a flexible conveyor providing a continuous work holding surface movable to and fro in said chamber between said heating section and said discharge section, means for actuating said conveyor in either direction in said chamber, a discharge opening in the base of the discharge section of said chamber, and selectively operable means for directing said conveyor in one direction of movement thereof, either into or across said discharge opening.

4. In a furnace, the combination of a chamber having a heating section and a discharge section, a door normally closing said chamber, a work holding conveyor having oppositely disposed ends, said conveyor being movable to and fro in said chamber between said heating section and said discharge section, a discharge opening in the base of the discharge section of said chamber, and means for operating said conveyor to and fro in said chamber, said means being operatively connected to one end thereof remote from said discharge opening whereby said other end is free to move into said discharge opening upon movement of said conveyor in the direction of said discharge opening.

5. In a furnace, the combination of a chamber having a heating section and a discharge section, a door normally closing said chamber, a work holding conveyor having oppositely disposed ends, said conveyor being normally completely contained within said chamber and movable to and fro between the heating section and said discharge section, said conveyor being composed of articulated conveyor elements, a discharge chute in the base of the discharge section of said chamber, means for operating said conveyor in either direction in said chamber, and guide means for directing one end of said conveyor into said discharge chute in one direction of its to-and-fro motion.

6. In a furnace, the combination of a chamber having a heating section and a discharge section, a door normally closing said chamber, a flexible work holding conveyor having oppositely disposed ends, said conveyor having upturned articulated marginal flanges movable to and fro within said chamber between said heating section and normally wholly contained within said heating section and said discharge section, a discharge chute in the base of the discharge section of said chamber, and guide means for directing one end of said conveyor through said discharge chute in one direction of its movement.

7. In a furnace, the combination of a chamber having a heating section and a discharge section, a door normally closing said chamber, a flexible work holding conveyor within said chamber,

means for moving said conveyor to and fro there-in between said heating section and said discharge section, a discharge opening in the discharge section of said chamber, and a bridging member movable across said opening to bridge the same whereby to effect conveyor movement across said opening or away from said opening to permit one end of said conveyor to move thereinto, in one direction of its to-and-fro motion in said chamber.

5 8. In a furnace, the combination of a chamber having a heating section and a discharge section, a door normally closing said chamber, a flexible work conveyor normally wholly contained within said heating section, means for moving said conveyor to and fro in said chamber between said heating section and said discharge section, a discharge chute depending from the discharge section of said chamber, a bridging member selectively movable across the entrance to said discharge chute or in position to leave said entrance open, and guide means for directing one end of said conveyor into said discharge chute in the latter position of said bridging member.

15 9. In a furnace, the combination of a chamber having a heating section and a discharge section, a door normally closing said chamber, means for operating said door to open position, a work holding conveyor movable to and fro in said chamber between the heating section and said discharge section said conveyor having one free end, a discharge chute depending from the discharge section of said chamber, means for operating said conveyor in either direction in said chamber, means for directing the free end of said conveyor into said discharge chute, and means for supplying a flow of protective atmosphere in said chamber and said discharge chute.

20 10. In a furnace, the combination of a chamber having a heating section and a discharge section, a door normally closing said chamber, means for operating said door to open position, a work holding conveyor movable to and fro in said chamber between said heating section and said discharge section, a discharge opening in the base of the discharge section of said chamber, and means controlled in accordance with the open or closed position of said door for directing said conveyor either across or into said discharge opening.

25 11. In a furnace, the combination of a chamber having a heating section and a discharge section, a discharge chute depending from the discharge section of said chamber, a flexible conveyor having a free end disposed within said chamber, means for operating said conveyor to and fro in said chamber between the heating section and the discharge section, a storage chamber carried by said discharge chute and opening thereinto, and means for directing the free end of said conveyor into said chute and through said opening in said storage chamber.

30 12. In a furnace, the combination of a chamber having a heating section and a discharge section, a discharge chute depending from the discharge section of said chamber, a flexible conveyor having a free end disposed within said chamber, means for moving said conveyor to and fro in said chamber between said heating section and said discharge section, a storage chamber carried by said discharge chute and opening thereinto, means for directing the free end of said conveyor in one direction of movement thereof, into said chute and through said opening in said storage chamber, and means for producing a gas

flow through said chamber, said chute and said storage chamber.

13. In a furnace, the combination of a chamber having a heating section and a discharge section, a discharge chute depending from said chamber, a flexible conveyor having a free end disposed within said chamber, means for moving said conveyor to and fro between said heating section and said discharge section, an opening in the side of said chute above the lower end thereof and guide means for directing the free end of said conveyor into said chute and through said opening.

14. In a furnace, the combination of a chamber having a heating section and a discharge section, a discharge chute depending from said chamber, a flexible conveyor having a free end disposed within said chamber, means for moving said conveyor to and fro between said heating section and said discharge section, and spaced guide means in said chute adapted to engage the free end of said conveyor in one direction of movement thereof to direct said end thereof into said chute.

HAROLD J. NESS. 25
